Application February 14, 1936, Serial No. 63,895

7 Claims. (Cl. 29—157.3)

(Granted under the act of March 3, 1883, as
amended April 30, 1928; 370 O. G. 757)

Our invention relates to a new and useful method of and apparatus for making heat or cold exchanging elements.

The objects of our invention are to provide a new and useful method of and apparatus for making heat or cold exchanging elements which will enable the production of such elements more rapidly and cheaply, of very high capacity for exchanging heat or cold, and which produced elements will be very light, strong and long enduring under the conditions encountered in use.

Other objects and advantages of our invention will be readily understood by those skilled in this art from the following specification.

15 In the drawings, Figure 1 is a side elevation view partially in cross-section of a heat or cold exchanging element illustrating typical steps in the transition of the product from its commencement until it is finished; the left end illustrating the commencement, and the extreme right end illustrating the finish;

Fig. 2 is a left end view of the parts shown in Fig. 1;

Fig. 3 is a view similar to Fig. 1 but including the apparatus arranged to produce the requisite transitions from the commencement to the completion of the finished product in accordance with our invention;

Fig. 4 is a right end elevation view of the parts shown in Fig. 3;

Fig. 5 is a left side view of a single typical one of the rows of bending and stretching tools, shown in Figs. 3 and 4;

Fig. 6 illustrates a detail of construction hereinafter described; and

Fig. 7 illustrates diagrammatically the front elevation view of a lathe or similar tool which may be employed in the practice of our method which may with substantially equal advantage be practiced by a number of different kinds of machines than herein indicated as will be understood by those skilled in this art.

In the drawings, in which like characters of reference indicate the same part, 10 represents the body portion of the heat or cold exchanging element which may be a tube or other shaped hollow body.

Heretofore, the heat or cold exchanging ribs or fins have been disposed edgewise upon the body portion of the element with the rib or fin throughout the operation, regardless of whether the rib or fin be longitudinal, or formed in a ring, or wound helically, invariably maintained with one edge in contact with the surface of the element and the width of the rib or fin extend-

ing substantially at a right angle from the body of the element. In winding or coiling the rib or fin edgewise about the body of the element and maintaining the rib or fin free from wrinkles and other objectionable surface irregularities substantial lateral stress is required to be borne by the body portion of the element. This lateral stress was occasioned by longitudinal stress upon the straight portion of the rib or fin as it was being advanced toward the stage of its edgewise bending or coiling about the body of the element, as well as further occasioned by the lateral stresses occasioned by the means for maintaining the ribs or fins at a right angle to the tube or body portion of the element. Despite the prior teachings of the art to wind the fin edgewise about the body portion of the element our present invention, in its method aspect indicated in Figs. 1 and 2 commences to wind or coil, helically or otherwise, the strip 11 about with one of its broad sides toward, the tube or body portion 10 of the heat or cold exchanging element. A broad thin flat ribbon of metal 11 is loosely advanced toward body portion 10, not under longitudinal or other stress, with one of its broad lateral faces substantially parallel with the outer surface of the tube or body portion 10. An end of said ribbon 11 is arranged in tangential contact with a surface of the tube or body portion 10, and, for instance, a narrow strip 12 at its left corner is secured to the tube or body portion 10 by solder or otherwise. Progressively with the coiling of said ribbon 11 about the surface of tube or body portion 10, a very narrow strip 12 of said ribbon 11 is progressively secured to said tube or body portion 10. As the ribbon 11 is progressively coiled around or helically about the tube or body portion 10, free from longitudinal stress, the unsecured side of a previously bent or coiled portion of ribbon 11 is simultaneously bent and stretched outwardly by progressive degrees until the main body of the rib or fin is formed at substantially right angles to its foot 12 which remains secured to the surface of the tube or body portion 10. The initial flat straight ribbon 11, as it approaches the tube or body portion 10, is in an unstressed condition which unstressed condition substantially continues in its portion bent about the tube or body portion 10 until the same commences to be bent, arched and stretched outwardly. Said outward bending, arching and stretching produces a very substantial longitudinal stress upon only the outwardly bent and stretched portion of the ribbon 11. However, such longitudinal stress tends to produce no sub-

stantial lateral thrust upon the tube or body portion 10 for the reason that such stress is unidirectional about the tube or body portion 10. Such longitudinal stress of the portion, other than the secured portion 12, of the ribbon 11, increases somewhat with the degree of outward bending or forming and stretching to which the same is progressively subjected until the main body of the ribbon 11 projects at substantially a right angle from the tube or body portion 10, in which latter position the right angle portion of the ribbon 11, which is of its normal thickness at its juncture with its foot 12, becomes progressively thinner as it extends beyond its foot 12. In this right angled or finished position of the main width portion of ribbon 11 some longitudinal stress is maintained in the rib or fin so formed from the flat unstressed ribbon 11. Such longitudinal stress is so maintained by the foot 12 as well as by its securement at progressive intervals or continuously to the wall of tube or body portion 10. This longitudinal stress maintained in the finished rib or fin enables a very much thinner and wider ribbon 11 of metal to be employed in the production of the rib or fin, because the same maintains such thinner formed rib or fin in its initially fixed position by said longitudinal stress substantially increasing its resistance to deformation and distortion, accidental or otherwise, as well as increases the rate of heat or cold exchange to or from the tube or body portion 10 by way of such formed and stressed rib or fin. In the outward bending and stretching of the main portion of ribbon 11, the same merely bends at the inner edge of the strip of metal along one edge of ribbon 11, which strip forms the foot 12.

The various progressive transition stages of the foregoing method of making the heat or cold changing element, from the bending or coiling helically, or otherwise, of the flat ribbon 11 flatways about the tube or body portion 10, until the completion of the product with the rib or fin standing upon its own foot 12 and at the desired angle from the tube or body portion 10, may all be performed by hand, or by metal spinning or by a number of existing mechanisms, with or without substantial modification of such mechanisms, as may be understood by those skilled in this art after becoming familiar with our method as well as our provided apparatus.

Our method and the apparatus which we have provided for practicing the same are related and dependent inventions. The apparatus portion of our invention substantially demonstrates the utility as well as practical value of the method portion of our invention. The apparatus portion of our invention furthermore materially contributes to the understanding of our invention by those skilled in this art, more particularly with respect to the practice of the method portion of our invention by hand, by spinning or by other forms of apparatus. The specific how and the details of each of these different ways of practicing the method are rendered more clear and definite by the understanding of the apparatus provided by applicants for the practice of their method.

In connection with the apparatus devised by us for the most economical, rapid and efficient practice of our method which we have thus far been able to devise, it will be understood by those skilled in the art that the tube or body portion 10 is mounted between the spindle and tail-stock centers of a lathe or like tool adapted to rotate

said tube or body portion 10. A roller 15 having a central bearing portion 16 revoluble in bearing member 17 is attached in any desirable manner to the usual cross-slide 17e, or other member, of the lathe or like tool which bears the usual tool post and in such relation to tube or body portion 10 that the peripheral portion 18 of roller 15 engages the narrow edge 12 of the ribbon of metal 11 so as to hold such portion of such ribbon firmly against the outer surface of the tube or body portion 10, with the adjacent face of shoulder 19 of roller 15 bearing against the outer lateral edge of portion 12 of ribbon 11.

The portion 18 of roller 15 is provided with a small narrow projecting bead 20. This bead 20 is either continuous or provided with short interruptions and extends completely around the peripheral portion 18 of roller 15, and it projects therefrom at a point intermediate the width of said portion 18 so as to engage a portion intermediate the width of portion 12 of ribbon 11. In operation, the bead 20 forms a shallow indentation 21 in the outer surface of portion 12 of ribbon 11. In thus forming indentation 21 adjacent metal of said portion 12 is forced inwardly and below the adjacent exterior surface of the tube or body portion 10, thus forming an indentation 22 in the exterior surface of tube or body portion 10. This secures portion 12 of ribbon 11 firmly to the tube or body portion 10 throughout the extent that a ribbon 11 may be formed or coiled about the tube or body portion 10. When the ribbon 11 is arranged in a straight line upon or about the body portion 10, the axis of roller 15 is disposed at a right angle to said straight line; but when ribbon 11 is, for instance, disposed at an angle to a direction of the body portion 10, for instance helically, the axis of roller 15 is disposed at a right angle to such angle, or to the course of the helix. A structure 40 admitting of such variable mounting of roller 15 is indicated in Fig. 6 in which the bearing member 17 comprises the outward end of the upper bend and of a standard 17a having a circular base 17b bearing in a recess in the upper surface 45 of the cross-slide 17e, or like member, of a lathe or similar tool which usually bears a tool post. Said base 17b is provided with a slot 17c through which, and a portion of cross-slide 17e, extends a bolt 17d for maintaining base 17b and standard 17a with roller 15 in any of their desired angular positions. To counteract the lateral deflection of tube or body portion 10 due to the thrust thereon of roller 15 one or more rollers 23 having bearings in member 23a adjustably secured to projection 24 of, or attached to, cross-slide 17e, by bolt 24a, facilitates the engagement of roller or rollers 23 with the tube or body portion 10 at a point or points opposite to and aligned with the point of engagement therewith 60 of roller 15. When the bead 20 is continuous, the depressions 21 and 22 are continuous, but when the bead 20 is interrupted the depressions 21 and 22 are correspondingly interrupted. In the latter case we have found that such brief 65 interruptions do not impair the securement of portion 12 of ribbon 11 to the tube or body portion 10.

A bar 25 extending preferably parallel with, but spaced apart from, an adjacent surface of the tube or body portion 10, is also mounted upon and supported by the cross-slide 17e, or other portion, of the lathe or like tool which usually bears the tool post. Removably secured to bar 25 by bolts 26c or otherwise, are a plurality of 75

separate tool shanks 27 which extend from bar 25 toward the tube or body portion 10. Upon the end of each shank 27 adjacent to the tube or body portion 10 is a preferable integral relatively thin portion 28 which is the segment of a hollow cone. The shanks 27 and their portions 28, are arranged at progressive intervals away from the unshouldered side of portion 18 of roller 15. In such progression the angles of the portion 28 of each shank 27 progressively varies. The portion 28 nearest the roller 15 being at an angle slightly below the horizontal, such most adjacent portion 28 extending inward and slightly downward from shank 27 and toward the roller 15, the edge portion thereof nearest the tube or body portion 10 being provided with a beveled edge 29, Fig. 3, to provide clearance between such edge 29 and the adjacent surface of tube or body portion 10 to accommodate the coiled portion of the ribbon 11. The angle of each succeeding portion 28 of each succeeding shank 27 is progressively increased until the portion 28 of the shank 27 most remote from roller 15 is at such angle that the surface of its portion 28 nearest to the roller 15 is at substantially a right angle, or such other angle relative to the tube or body portion 10 that the finished rib formed from ribbon 11 is desired to stand relative to the tube or body portion 10.

The operation of the mechanism thus far described will now be explained with relation to the helical coiling of the ribbon 11 about the tube or body portion 10 which latter is inserted in the lathe adjacent the tip ends of portions 28 and between rollers 15 and 23 and mounted between centers 50, 52 and mounted in any usual manner to be rotated by the lathe. The cross slide 17e is moved, with the parts 17a, 24, 25 and their attachments mounted thereon, adjacent center 51. As is usual with lathe work which may be performed only within an area between centers 50, 52 in which the required tools will not be interfered with, the ribbon 11 may be wound or helically coiled upon tube 10 within such area. In this case such area commences under roller 15 when the cross slide 17e is in said moved position and may continue toward center 52 and terminate at such point on tube 10 that roller 15 and portions 28 and their associated parts may have clearance between center 52 and the terminal coil of ribbon 11 after the last of portions 28 have acted upon the terminal portion of the coiled ribbon 11a which the uncoiled ribbon is severed from the coiled portion thereof. The length of the tube 10 employed being such as will afford the required length of the coils of ribbon 11 thereon, as well as said clearance spaces at both ends of the tube 10. The angularity required for such desired helical coiling is fixed by the adjustment and securement of base 17b to 17e. This likewise correspondingly adjusts the guide for ribbon 11 in its approach to roller 15. Said guide may be conveniently formed of a projecting arm 17f extending from bearing member 17 and having a slot 17g in its outer end through which the ribbon 11 loosely extends toward the roller 15. Ribbon 11 is led from a convenient roll or other source of supply loosely through slot 17g and thence without longitudinal or other stress to the roller 15. The loose end of ribbon 11 is placed between tube or body portion 10 and surface 18 of roller 15 with its adjacent edge against shoulder 19 of roller 15, the remaining portion of ribbon 11 resting upon a portion of the outer surface of hollow conical portion 28 of the most adjacent shank 27. The rotation of tube or body portion 10 between the centers of the lathe or like tool will cause the helical coils about tube or body portion 10 of the ribbon 11 when the end of ribbon 11 is forced between the tube and roller 15 in the position before stated. It will be understood by those skilled in the art that the lathe or like tool will also be set to longitudinally move the cross-slide 17e relative to the rotating tube or body portion 10 at the rate corresponding to the required angle at which the ribbon 11 is to be helically coiled about the tube or body portion 10. In such helical coiling of the ribbon 11 about the tube 10 its portion 12 will be firmly and continuously secured to the tube or body portion 10 by the interlocking metal comprising the depression 22, as well as further by the fact that the ribbon 11 extends repeatedly around the tube or body 10. This securement of the portion 12 of ribbon 11 also forms a slight bend in the ribbon 11 at a point between its portions 11 and 12 due to the securing pressure of roller 15 upon portion 12 of ribbon 11 while the portion 11 thereof is resting upon the outward conical surface of portion 28 of shank 27 nearest to roller 15. In the progression of this coiling of ribbon 11 about the tube or body portion 10 the engagement of the inner surface of ribbon 11 with the exterior surface of said hollow conical segmental portions 28, as the end of the original ribbon 11 starts to be so coiled, tends to slightly outwardly bend as well as stretch the coiled portion of ribbon 11 by and throughout the extent the angularity of the engagement of the initial hollow conical segmental portions 28 of shanks 27. This engagement also exerts a spinning action upon the coiled portion of the ribbon 11 which progressively bends as well as stretches the metal of ribbon 11, and which stretching occurs most at the unsecured edge of ribbon 11 and least or practically nothing at the point between the portions 10 and 11 of the ribbon. As the ribbon continues its coiling beyond the point where it engages with the initial segmental portion of the hollow cone 28 of shank 27 nearest roller 15, the end of the coiled ribbon 11 extends about the tube or body 10, under and free from the inner surface of the before mentioned portion 28, thence again completely around the tube or body portion 10 until the same engages the exterior surface of a similar portion of the next succeeding hollow cone 28 having a similar shank 27 but slightly more inclined than the first portion 28. This second portion 28 further bends and stretches the coiled ribbon progressively at a further angle from the tube or body portion 10. From this point onward the coiled portion of ribbon 11 at every alternate coil is engaged by a further separate portion 28, each of progressively greater inclination, and each separately supported by its own shank 27, and each further progressively outwardly bending and stretching the wound ribbon 10, by reason of said portions 28 being each outwardly inclined on their outer surfaces at a progressively increasing angle, until the coiled ribbon 11 is finally finished and projects from the tube or body portion 10 at the desired angle, which is usually a right angle. The outward bending and stretching of the ribbon 11, while it is being formed about the tube or body portion 10 by the separate slight progressive changes due to the successive and progressive action on such ribbon by each of the successively spaced and positioned portions 28 of different angularities thins the metal of the outwardly bent portion of 75

ribbon 11, the outer edge of the formed ribbon of metal being the thinnest, and the intermediate of the formed ribbon being substantially progressively thicker at intermediate points 5 throughout the width, and thickest (being of the normal thickness of ribbon 11) at the point of juncture of the formed ribbon 11 with its substantially right angled foot 12. This bending and stretching of the outer portion, as distinguished 10 from portion 12, of the ribbon 11 while it is being formed is caused by the frictional engagement of the portions 28 progressively with the same under surface of the ribbon 11, while being formed. The temperature resulting from such 15 engagement, coincident with the longitudinal stress created in the ribbon 11 while being bent outwardly concurrently contribute to the stretching action of the metal. The longitudinal stress, and therefore the stretching, is greater at the 20 outer edge of the ribbon 11 while being formed, and progressively less at its inner edge where such stress is practically neutral, and such progressively increasing degrees of stress remain in the ribbon after it has been completely formed, 25 such continuing stress being however less than required to stretch the metal of the ribbon 11. This permanent longitudinal stress in the finished product of the formed ribbon 11 about the tube or body portion 10 accomplishes a number of 30 important results, accomplishments and advantages, the primary ones being:—

(a) Enables a much thinner and wider ribbon 11 to be employed than was heretofore possible, which greatly increased the lightness, cost, number of coils of ribbon 11 per unit of length, increased the heat or cold exchanging rate and consequently reduced the size, space and weight requirements for such exchange unit to attain a given exchange capacity;

(b) Such wider, thinner coils of ribbon 11 in 40 greater number per unit of length of the tube or body portion 10, which would otherwise be less stable and more readily deformed and laterally bent together or of unequal spacing apart are by 45 our method and apparatus provided with a substantial longitudinal stress which is uni-directional about and exerts no lateral deflecting influence upon the tube or body portion 10 notwithstanding the magnitude of such longitudinal stress; that the ribbon 11 is devoid of such stress 50 as it approaches the point of being wound about the tube or body portion 10; that said stress progressively stretches the metal of the ribbon 11 while being formed about the tube or body portion 10 and such stress continues in the finished 55 product to a degree less than that required to further stretch the metal of the finished formed ribbon 11. Such permanent stress of the metal of the finished formed ribbon 11 gives greater 60 stability and resistance to deformation and lateral bending of each of the finished formed portions of the ribbon 11, as well as increases the rate of conductivity of heat or cold of the metal of such formed and stressed portions of ribbon 11 due not only to the cold working of the ribbon 11 in forming the same, but to the stretching as 65 well as the permanent stress in the formed ribbon 11; and

(c) The greater rapidity of the production of 70 the finished heat exchanger element in accordance with our invention increases the cheapness of the same without detracting from but increasing the quality, efficiency, and durability of the finished product; the freedom from complexity of required production mechanism and the

greater useful life of the required production mechanism, due to the absence of the substantial longitudinal stress upon the ribbon 11 at the point where it commences to be wound about the tube or body portion 10; the pleasing uniform 5 high polished appearance of the finished product; the ability to employ a very wide much thinner ribbon 11 than was possible to heretofore use without precoiling edgewise to a diameter larger than the tube or body portion 10 before coiling 10 the same upon each tube or body portion; the requirement that the tube or body portion 10 may have a thin wall no more than necessary to resist the pressure and corrosion or other deteriorating action thereon in normal use because 15 such wall requires no grooving or other working, which may lessen its resistance, requisite to the winding and securing of the ribbon thereabout, but instead thereof the ribbon 11 is coiled about the virgin unworked wall of the tube or body portion 10 and the strength and resistance of the wall of the tube or body portion 10 is increased 20 by the flat winding thereabout of the foot 12 under no initial longitudinal stress but whose bent side is subjected to inward and/or longitudinal stress resulting from the bending and stretching of the metal of the ribbon 11 extending outwardly from such side of the foot 12, as well as by the continuous or slightly interrupted row comprising the depression 21 in the foot 12 resulting 25 in the slight depression 22 in the outer wall of the tube or body portion 10 with metal of foot 12 interlocked in such depression 22, which depression and the cold working of the metal resulting in their formation, tend substantially to 30 reinforce the strength and resistance of the substantially thinner wall of the tube or body portion 10.

One of the bending and stretching portions 28 acting upon ribbon 11 while it is being coiled, bent and stretched about the tube or body portion 10 is illustrated in Fig. 5 which shows an end elevation view thereof looking toward it from the direction of roller 15. Instead of the portions 28, ordinary spinning tools or, rods or sticks may be employed to progressively bend and stretch the ribbon 11 about the tube or body portion 10. 40

It will be noted from Fig. 3 that in the form of the apparatus therein disclosed the forming-by-bending-and-stretching portions 28 engage the 45 wound ribbon 11 at but one point in at least every other coil of the ribbon 11 about the tube or body portion 10. This affords a substantial area of the ribbon 11 to transmit the heat engendered by such cold working operations as said bending and stretching, to the metal of the tube or body portion 10 by conductivity through the metal of the ribbon 11 as well as very large surface areas of the metal of ribbon 11 exposed 50 to the atmosphere throughout points thereof which are contacted by said portions 28, and which conduction to the atmosphere of such surplus heat of the ribbon 11 in its successive forming stages is very substantial and results in a 55 very efficient, cheap, durable and highly finished product being very rapidly made from the metal comprising the ribbon 11 which may be most advantageous for the employment of the apparatus shown in Fig. 3. Such heat exchange to the atmosphere throughout the area of ribbon 11 60 engaged by successive portions 28 is very substantial for the further reason that the rotation of tube or body portion 10 with the wound portion of the ribbon 11 is very rapid and this, together with the progressive outward bending and 65

stretching of the metal of ribbon 11 creates a substantially increased circulation of air around and between the coils of ribbon 11.

Any number of bars 25 supported by cross-slide 17e may be employed each with its row of shanks 27, with their respective portions 28 at different radial points about the tube or body portion 10. Fig. 4 illustrates such an arrangement in which three bars 25 are employed each with attachment similar to those shown and described relative to Fig. 3, each bar 25 being substantially equally spaced about the tube or body portion 10. In such arrangement the segmental hollow conical portion 28 of each shank 27 are of such segmental dimensions that ample space is afforded between the adjacent portions 28 to not only enable their insertion and removal, but also to afford a substantial area of ribbon 11 exposed to the atmosphere and the affordance of substantial heat conductivity from such exposed portions of ribbon 11 to the atmosphere.

In Fig. 7 is shown a diagrammatic view of a lathe or other tool in which the tube or body portion 10 is mounted between the conical centers 50 of tail-stock 51 and 52 of head-stock 53. The conical center 52 of head-stock 53 being rotated by power pulley or motor 54, which correspondingly drives a pulley 55 belted by belt 56 to pulley 57 upon a shaft 58 mounted in bearings 59 on base plate 60, said shaft 58 being provided with screw threads 61 engaging a suitable nut mounted upon the cross-slide 17e for imparting longitudinal motion to said slide 17e along base plate 60 at the rate required to obtain the desired pitch of the helical coils of ribbon 11 about the tube or body portion 10. To vary such rate any one of different sized pulleys 55 or equivalent means may be employed. In conventional view, Fig. 7, the details indicated in Fig. 6 are not disclosed for clearness.

To increase the rate of conductivity of the surplus working heat from the portions of the ribbon being bent and stretched and from the portions 28 which perform such functions, each shank 27 may be provided with a longitudinal opening 70 opening to the atmosphere at its end adjacent portion 28 and having its upper end connected to a pipe 72. Air or other fluid under any desired pressure may be passed through pipe 50 72 and opening 70 to and around adjacent surfaces of the ribbon 11 and portions 28 to further increase the rate of heat conductivity occasioned by the cold working of the portions of the ribbon 11 formed about the tube or body portion 10. The rate of such heat transfer may be controlled by varying the pressure of the fluid conveyed to each opening 70.

Our invention in each of its related and dependent aspects of method and of apparatus will be readily understood and usable by those skilled in this art from the foregoing specifications.

This invention may be made and used by or for the Government of the United States of America for governmental purposes without the payment of any royalty thereon or therefor.

Having now so fully described our invention that others may therefrom be enabled to practice, construct and use the same, what we claim is:—

1. The method of making a heat exchange device including a heat exchange element provided with a heat exchange fin secured thereto, comprising the steps of securing a portion of a metal strip to a heat exchange element to form at least

one convolution thereabout and then progressively bending the unsecured portion of the strip outwardly of the heat exchange element and angularly with respect to its secured portion to directly form by the bending operation a heat exchange fin circumferentially secured to a heat exchange element. 5

2. The method of making a heat exchange device including a heat exchange element provided with a helical heat exchange fin secured thereto, 10 comprising the steps of helically securing a portion of a metal strip to a heat exchange element and then progressively bending the unsecured portion of the strip outwardly of the heat exchange element and angularly with respect to its 15 secured portion to directly form by the bending operation a helical heat exchange fin secured to a heat exchange element.

3. The method of making a heat exchange device including a heat exchange element provided with a helical heat exchange fin secured thereto, 20 comprising the steps of helically securing a portion of a metal strip to a heat exchange element with adjacent convolutions of the unsecured portion of the strip in overlapping relation and then progressively bending the unsecured portion of the strip outwardly of the heat 25 exchange element and angularly with respect to its secured portion to directly form by the bending operation a helical heat exchange fin 30 secured to a heat exchange element.

4. The method of making a heat exchange device including a heat exchange element provided with a helical heat exchange fin secured thereto, 35 comprising the steps of helically securing a portion of a metal strip to a heat exchange element with adjacent convolutions of the unsecured portion of the strip in overlapping relation, then progressively bending the unsecured portion of the strip outwardly of the heat exchange element and angularly with respect to its secured 40 portions to directly form by the bending operation a helical heat exchange fin secured to a heat exchange element and cooling the metal of the strip during the bending operation. 45

5. An apparatus for making a heat exchange device including a heat exchange element provided with a helical heat exchange fin secured thereto, comprising means for helically securing a portion of a metal strip to a heat exchange element and means for progressively bending the unsecured portion of the strip outwardly of the heat exchange element and angularly with respect to its secured portion to directly form by the bending operation the helical heat exchange 55 fin, said last mentioned means including a plurality of spaced members of varying and progressive angulation with respect to the element to be finned and arranged lengthwise thereof. 60

6. An apparatus for making a heat exchange device including a heat exchange element provided with a helical heat exchange fin secured thereto, comprising means for helically securing a portion of a metal strip to a heat exchange element and means for progressively bending the 65 unsecured portion of the strip outwardly of the heat exchange element and angularly with respect to its secured portion to directly form by the bending operation the helical heat exchange fin, said last mentioned means including a row of 70 spaced overlapping members having a varying and progressive angulation with respect to the element to be finned and arranged lengthwise thereof. 75

7. An apparatus for making a heat exchange

device including a heat exchange element provided with a helical heat exchange fin secured thereto, comprising means for helically securing a portion of a metal strip to a heat exchange element and means for progressively bending the unsecured portion of the strip outwardly of the heat exchange element and angularly with respect to its secured portion to directly form by the bending operation the helical heat exchange fin,

said last mentioned means including a plurality of spaced members of varying and progressive angulation with respect to the element to be finned and arranged lengthwise thereof, at least one of said members being apertured for the introduction of a cooling fluid. 5
